UNITED STATES PATENT OFFICE.

JOHN R. DERRICK, OF ROANOKE, VIRGINIA.

LUBRICATING DEVICE.

Application filed April 16, 1926. Serial No. 102,474.

This invention relates to a lubricating device for association with a railway track, and has for its primary object to provide simple and reliable means for automatically oiling 5 engine and car wheel flanges and the track rails at curves.

The friction between the rails and the flanges of the wheels of engines and railway cars, as is well known, is productive of rapid 10 wear of the rails and wheel flanges, particularly during the passage of a train around a curve. As a result the life of car wheels and of rails at curves is greatly reduced. By my invention, however, as has been 15 demonstrated by actual use, efficient and practical means are provided for applying lubricant to the car wheels and rails, thereby minimizing the wear upon them.

The principal feature of the invention 20 consists in disposing a lubricant reservoir adjacent the inside or gage side of the web of one of the track rails, and in combining therewith a movable wiper for receiving lubricant from the reservoir and applying it to 25 the part to be lubricated, means being provided for actuating the wiper by movement of the rail resulting from the passage of a car truck over the track.

A further feature of the invention consists 30 in operating wipers for applying lubricant to the part to be oiled by means of mechanism which is actuated as a result of the deflection or depression of a portion of one of the track rails with which the lubricating 35 device is associated, said mechanism including a clutch adapted to release when overloaded.

Another feature of the invention resides 40 in the employment of means for promoting equal distribution of the lubricant in the reservoir of the lubricating device.

Other features of the invention pertaining 45 to advantageous constructions and relations of parts will hereinafter appear and be pointed out in the claims.

In the drawings illustrating preferred embodiments of the invention,—

Figure 1 is a plan view of an end portion 50 of a lubricator involving the invention, showing its manner of association with the

adjacent rail of a railway track, the head of the rail and a portion of the cover of the lubricant reservoir being cut away to more clearly disclose the construction.

Figure 2 is a side elevational view of the 55 construction shown in Fig. 1.

Figure 3 is a view corresponding to Fig. 1, but illustrating the opposite end of the lubricating device.

Figure 4 is a side elevational view of the 60 portion of the construction shown in Fig. 3.

Figure 5 is a detail sectional view on the line 5—5, Fig. 1.

Figure 6 is a detail sectional view on the line 6—6, Fig. 5.

Figures 7, 8 and 9 are detail sectional views on the line 7—7, 8—8, and 9—9, respectively.

Figure 10 is a detail view in vertical section showing one of the oil breakers and 70 parts of the mechanism adjacent thereto, the view being taken on the line 10—10, Fig. 11.

Figure 11 is a detail sectional view on the line 11—11, Fig. 10.

Fig. 12 is a diagrammatic view illustrating the preferred disposition of the lubricating device with respect to the railway track and associated guard rail.

Figure 13 is a vertical sectional view of a modified form of the invention, showing its 80 application to the adjacent track rail, the cover plate of the lubricant reservoir being omitted.

Figure 14 is a detail sectional view on the line 14—14, Fig. 13, a portion of the car 85 wheel being also illustrated.

As indicated in Fig. 12, the lubricant reservoir 2 is placed between the rails 1 of the track while a guard rail 3 is preferably positioned opposite the reservoir so as to 90 provide means for preventing the oil applying disks from being crushed between the flanges of the engine or car wheels and the side of the adjacent main track rail head. The guard rail by preventing lateral motion 95 of the passing wheels also serves to retain their flanges in proper contact with the oilers or disks while the wheels are passing the lubricating device. The length of the oil reservoir as measured along the track is pref- 100

erably sufficient to ensure application of the lubricant to the entire circumference of car wheels of the size now commonly employed.

The lubricant reservoir 2 is preferably formed as a metallic trough provided with a detachable cover 4 which is notched or recessed at intervals, as indicated at 5, to permit the oil applying disks or wipers to project above the reservoir. The body of the reservoir may conveniently be made of sheet metal while its ends are preferably constituted by angular bars or brackets 6 welded to the sheet metal body portion. The brackets 6 are perforated to receive bolts 7 which extend through the web of the adjacent rail and thereby serve to maintain the mechanism in proper position. As well shown in Fig. 7, the lubricant reservoir is positioned below the path of travel of passing wheels 8, but the wipers or disks 9 by which the lubricant is applied to the parts to be lubricated extend upwardly sufficiently far to contact with the inner surface of the flanges of the wheels. The disks 9 are preferably made of an absorbent resilient substance, such for example as leather, and their circumferences are preferably somewhat beveled so as to conform generally to the inclination of the inner surface of the flanges. A heavy oil has been found to be a suitable form of lubricant, the reservoir 2 being filled therewith to a depth permitting the oiler disks to dip well below the surface thereof.

Within the lubricant reservoir is a frame serving as a mounting for certain movable parts of the device and enabling the wipers or disks to be adjusted with relation to the neighboring rail head and wheel flanges to be lubricated. This frame may advantageously consist of oppositely disposed side bars 10 having welded to the respective inner sides thereof nuts 11 for receiving threaded bolts whose headed lower ends rest upon the bottom of the reservoir. By manipulating the bolts 12 the side bars 10 may be raised or lowered in the lubricant reservoir, as will be readily understood. To maintain these bolts in their respective positions of adjustment, bolt locks 13 are preferably employed. As well illustrated in Figs. 7, 8, 10 and 11, these bolt locks may advantageously be U-shaped members which rest upon the bottom of the reservoir 2 and engage the sides of the latter. The inwardly extending legs of the bolt locks are slotted, the slots 14 in the lower legs being of a form to prevent rotation of the bolts 12, whose heads cooperate therewith. Raising the bolt locks 13 upwardly permits the adjusting bolts 12 to be turned, but when the bolt locks are in normal position their engagement with the sides of the lubricant reservoir 2 prevents turning of the bolts, as will be readily understood. Lengthwise adjustment of the side bars 10 is preferably effected by means of a

pair of adjusting screws 15 (see Fig. 8) which are respectively secured to the bars and pass outwardly through the adjacent end of the reservoir. Inner and outer adjusting nuts 16 and 17, respectively, cooperate with each of the adjusting screws 15. As will hereinafter be apparent, the longitudinal adjustment of the side bars 10 serves to take up slack in the sprocket chain by which the rotary wiper disks are actuated.

Journalized in the side bars in spaced relation to each other along the track are a plurality of shafts 18 carrying the wipers 9, and alternating therewith are intermediate shafts 19 and 20, respectively, supported by the side bars 10.

Loosely mounted on the intermediate shafts are idler rollers 21 and baffles or oil breakers 22 and 23. The idler rollers 21 engage the upper segment of the sprocket chain 24, thus serving to maintain the chain in efficient operating relation to the sprocket wheels cooperating therewith. The oil breakers 22 and 23, which preferably are formed of sheet iron, extend toward the bottom of the reservoir 2 on opposite sides of the sprocket chain 24 and serve to prevent the latter from causing oil to accumulate unduly at one end of the trough.

The adjustable shafts 19 provide means for forcing the side bearing bars outwardly against the lateral walls of the lubricant reservoir. They preferably consist of a shaft member 25 (see Fig. 11) threaded at its inner end for cooperation with a shaft member 26 constituting a threaded sleeve or nut. The outer ends of the sections 25 and 26 of the adjustable shafts project into suitable seats or socket bearings 27 of the frame members 10, and said shaft members are maintained in adjusted relation by means of cooperating lock nuts 28.

For the purpose of securing the disk wipers 9 to their respective shafts 18 each of the latter is preferably formed intermediate its ends with an enlargement or collar 29. To the inner end of this collar an annular steel plate 30 is welded. Between this plate and an annular plate 31 the leather disk wiper 9 is positioned, the plate or washer 31 being slipped upon the end of the shaft 18 and secured to the annular plate 30 by means of rivets 32 passing through the leather disk. In order to permit the wiper disks 9 to adjust themselves for contact with the flanges of passing wheels, each of the disk operating shafts 18 is designed to yield in the direction of its length. For this purpose the end of each shaft 18 nearer the chain is encircled by a spring 33 operatively interposed between the plate 31 and the adjacent side bar 10 in which the shaft is journaled. These springs tend to force the wiper disks 9 away from the head of the rail and into contact with the flanges of passing wheels. The

shafts by which the disks or oilers are carried are respectively provided with sprocket wheels 34 for cooperation with the driving sprocket chain 24.

At one end of the reservoir 2 is a driving shaft 35 extending from the reservoir through the web of the adjacent track rail. This shaft preferably extends through the web of the rail at or about the center thereof and projects somewhat beyond the outer edge of the rail base. Secured to the end of the shaft within the lubricant reservoir (see Fig. 5) is a sprocket wheel 36 for driving the sprocket chain 24. Surrounding the intermediate portion of the driving shaft 35 is a bearing sleeve 37 which passes through the web of the rail and extends into the lubricant reservoir. Welded to this sleeve toward its outer end is a bar or bracket plate 38 secured to the rail by means of the bolts 7. Surrounding the sleeve 36 on the inside of the web of the rail are steel washers 39 which space the lubricant reservoir 2 a short distance from said web. To prevent oil from leaking from the reservoir through the opening for the driving shaft 35 a compressible washer 40, preferably made of felt, encircles the sleeve 37 and bears against the adjacent inner face of the reservoir. Metallic washers 41, which are interposed between said felt packing washer and a clamping nut 42 having threaded engagement with the inner end of the sleeve 37, serve to maintain the compressible washer 40 in proper contact with the parts to be packed.

Jounaled on the driving shaft outside of the rail is a ratchet wheel 43 placed between two friction washers 44 which preferably are made of fiber. The inner fiber washer 44 bears against a circular flange or clutch plate 45 with which the driving shaft 35 is provided, while the outer fiber washer is overlaid by a metallic plate or washer 46 which is pressed inwardly of the shaft by means of a spring 47. The spring is maintained on the shaft by means of a nut 48 carried by the latter. By turning the nut 48 the spring 47 may be compressed so as to induce sufficient friction between the ratchet wheel 43, the flange 45 of the shaft, and the intervening fiber washer 44, thus enabling the ratchet wheel to drive the shaft 35 under conditions of normal load, but permitting slippage or release of the ratchet wheel in the event of overload. This clutch mechanism is preferably incorporated in the lubricating device for the sake of preventing injury to the parts.

The two cross ties 49 between which the ratchet wheel is situated are spaced a short distance downward from the base of the track rail, thus providing a yielding section of the rail which is compressible by the passage of car trucks thereover. As the ratchet wheel 43 oscillates vertically in response to

the vibrations of the compressible rail section, it is caused to rotate by pivoted pawls 50 and 51, respectively, the former being a push pawl and the latter a drag pawl. These pawls may conveniently be retained in operative relation to the ratchet wheel by means of a connecting spring 52. At their lower ends the pawls 50 and 51 are pivotally secured by means of a threaded stud 53 and cooperating nut to a bracket 54 whose upper end is forked or bifurcated to receive and permit vertical movement of the driving shaft 35 on which the ratchet wheel is mounted. The lower portion of this bracket extends outwardly and is secured by bolts 55 to the depressed central portion of an anchoring bracket or base member 56 which is firmly secured to the two cross ties 49 adjacent the ratchet mechanism. A sheet metal cover 57 secured to the upper end of the bifurcated vertical bracket 54 by bolts 58 may advantageously be employed for shielding the ratchet mechanism from the weather.

In the modified form of the invention illustrated in Figs. 13 and 14, the lubricant is applied by means of wipers formed as tabs 59 of leather or fibrous material secured to a continuous sprocket chain 60 whose lower segment travels through the oil in the reservoir. At its opposite ends the sprocket chain cooperates with sprocket wheels 61 and 62, respectively, the former being an idler and the latter serving to drive the chain.

The driving shaft 63 to which the sprocket wheel 62 is secured is preferably actuated by ratchet mechanism such as that employed for turning the driving shaft 35 of the form of lubricating device heretofore described. The lubricant reservoir is provided with a detachable cover 64, preferably a spring steel sheet, forming a support for the upper segment of the sprocket conveyor chain and oilers for substantially the full length of the reservoir. The sprocket chain is preferably made of sufficient length to permit the full circumference of standard car wheel flanges to be oiled by successive wipers or tabs 59 as the wheel passes along the lubricating device.

A longitudinally extending groove or channel 65 is preferably formed in the cover plate for receiving the upper segment of the chain belt. A series of springs 66 arranged at intervals may advantageously be employed for supporting the cover member of the reservoir.

Referring to the construction shown in the principal figures of the drawings, when an engine or a car truck passes over the rail at the point where the ratchet mechanism is located, the rail is depressed, due to the imposed load, and the ratchet wheel 43 moves downwardly. As the pawls 50 and 51 which cooperate with the ratchet wheel are sustained against vertical movement because

of being mounted upon the vertical bracket 54 secured to the cross ties, the pawl 50 causes the ratchet wheel 43 to revolve as it moves downward, while the pawl 51 effects 5 a driving rotation thereof when the section of track rail adjacent the ratchet is relieved of the weight of the engine or car truck, and springs upwardly toward normal position. The revolution of the ratchet wheel 10 causes the rotation of the shaft 35 carrying the driving sprocket 36 around which the sprocket chain 24 passes. The moving sprocket chain, acting through the sprocket wheels 34, in its turn causes a rotation of 15 the shafts on which the wiper disks 9 are mounted, thereby causing these disks to dip into the lubricant of the reservoir and carry said lubricant upwardly so as to apply it to the flanges of the passing wheels. The 20 engine and car wheels in turn apply the oil to the flange engaging surface of the rails, thereby preventing both flange wear of rail on curves and wear of engine and car wheel flanges.

25 In the modified form of construction the travel of the chain belt 60 induced by the passing of a train causes the wipers which are carried by the segment of the chain which is uppermost at the time to apply the 30 lubricant to the flanges of the passing wheels, as will readily be understood.

I claim:—

1. A lubricating device for association with a railway track having a depressible 35 rail section, involving a lubricant reservoir secured to and movable with the rail, means movable with respect to said reservoir for elevating the lubricant to the part to be lubricated, and mechanism for operating 40 said means, said mechanism including a ratchet wheel adapted to be bodily moved vertically by the depression of a track rail caused by the passage of a railway vehicle 45 thereover, and a plurality of pivoted pawls alternately adapted to rotate said ratchet wheel in the same direction.

2. A lubricating device for association 50 with a railway track, involving a lubricant reservoir, means movable with respect to said reservoir for supplying lubricant to the part to be lubricated, and means for actuating said first named means involving a ratchet member and a plurality of cooperating pawl members, each of said pawl 55 members being relatively movable with respect to said ratchet member to alternately effect a rotation of the latter in the same direction, and at least one of said members being movable with a depressible rail section 60 to which said reservoir is rigidly secured.

3. A lubricating device for association 65 with a railway track, involving lubricating means positioned between the track rails and adjacent one of said rails, and a guard rail

opposite said means and fixed with respect thereto, said guard rail positioned adjacent the other rail of the track and serving to limit lateral movement of car trucks with respect to said means.

4. A lubricating device for association 70 with a railway track, involving a lubricant applying member positioned adjacent the inner side of one of the track rails so as to be adapted to extend between a rail of the 75 track and the flange of a car wheel cooperating therewith, and a guard rail positioned opposite said member adjacent the inner side of the other track rail for limiting lateral movement of said flange toward the adjacent side of said rail.

5. A lubricating device for association 80 with a railway track, involving a lubricant reservoir positioned below the path of travel 85 of the car wheels, movable means for receiving lubricant from the reservoir and transferring it to the part to be lubricated, said movable means normally tending to assume a position out of contact with the adjacent rail head, and means for adjusting 90 the angular position of said first named means to compensate for wear of the latter and also of the adjacent track rail and the flanges of car wheels passing thereover.

6. A lubricating device for association 95 with a railway track, involving a lubricant reservoir, a plurality of rotary disks adapted to dip into the lubricant and to transfer the latter to the part to be lubricated, said disks being adapted to extend between the 100 head of the adjacent rail and the flange of a cooperating car wheel passing thereover, springs respectively tending to move said disks away from the said rail head and means for adjusting the angular position 105 of said disks to compensate for their wear and that of the adjacent rail and flanges of car wheels.

7. A lubricating device for association 110 with a railway track, involving a lubricant reservoir, a plurality of spaced shafts, a frame in which said shafts are journaled, and wipers respectively secured to said shafts and adapted to apply the lubricant to the part to be lubricated, said frame being vertically adjustable and said shafts being 115 yieldingly movable in their direction of length.

8. A lubricating device for association 120 with a railway track, involving a lubricant reservoir, a plurality of spaced shafts, wipers mounted on the respective shafts and adapted to apply the lubricant to the part to be lubricated, and means for revolvably supporting said shafts, said means being adjustable vertically and in the direction of 125 length of the track.

9. A lubricating device for association 130 with a railway track, involving a lubricant reservoir, a plurality of spaced rotatable shafts, each of said shafts being provided

- with a sprocket wheel whereby it may be driven, a sprocket chain co-operating with the sprocket wheels, said chain being positioned in the reservoir and having one of its segments adapted to travel in the lubricant, means actuated by the movement of said chain for applying the lubricant to the part to be lubricated, and means arranged between said shafts for opposing unequal distribution of the lubricant in the reservoir as a result of the inmovement of the chain. 70
10. A lubricating device for association with a railway track, involving a lubricant reservoir, a plurality of spaced rotatable shafts, each of said shafts being provided with a sprocket wheel and with a disk for applying the lubricant to the part to be lubricated, a frame disposed within the reservoir and forming a support for the shafts, 75
- 15 a sprocket chain cooperating with the sprocket wheels to drive the shafts, said frame involving oppositely disposed side bars extending along the track, and intermediate adjustable shafts for positioning 80
- 20 said side bars with respect to each other. 85
11. A lubricating device for association with a railway track, involving a lubricant reservoir, a plurality of spaced rotatable shafts each provided with a sprocket wheel 90
- 25 and with a disk for applying the lubricant to the part to be lubricated, a sprocket chain cooperating with the sprocket wheels, said chain being disposed in said reservoir in spaced relation to the sides of the latter, and 95
- 30 breaker members for the lubricant positioned in the reservoir and disposed between adjacent disks on opposite sides of the said chain. 100
12. A lubricating device for association with a railway track, involving a lubricant reservoir, means for applying the lubricant to the part to be lubricated, and mechanism actuated by the passage of a car over the track for operating said means, said mechanism including a clutch device adapted to 105
- 35 release when overloaded. 110
13. A lubricating device for association with a railway track, involving a lubricant reservoir, means extending into said reservoir for applying lubricant to the part to be lubricated, mechanism for actuating said means including a plurality of sprocket wheels and a cooperating sprocket chain, said sprocket chain being arranged in the reservoir and having one segment adapted 115
- 40 to pass through the lubricant, and means positioned in said reservoir at the side of said chain operating to oppose collection of the lubricant at one end of the reservoir. 120
14. A lubricating device for association with a railway track involving a lubricant reservoir positioned on the inner side of an adjacent track rail below the path of travel of the car wheels, means for applying the lubricant to the part to be lubricated, and mechanism operated upon the passage of a car over 125
- 45 the track for actuating said means, said mechanism being adjacent the outer side of the said track rail with which the lubricant reservoir is associated and being connected to said rail so as to be actuated thereby. 70
15. A lubricating device for association with a railway track, involving a lubricant reservoir, means for applying lubricant to the part to be lubricated, chain and sprocket mechanism for actuating said means, and a driving device for said chain, said driving device involving a shaft extending through the web of the adjacent rail and provided with a sprocket cooperating with the chain and also including a pawl and ratchet means 80
- 50 for actuating said shaft upon the passage of a car over the track, said sprocket and said pawl and ratchet means being upon opposite sides of the rail. 85
16. A lubricating device for association with a railway track, involving a lubricant reservoir, means for applying the lubricant to the part to be lubricated, and mechanism for actuating said means, said mechanism including revolvable shaft extending from the reservoir through the web of the adjacent track rail and provided with a ratchet wheel fixed to said shaft, said track rail being between the reservoir and the ratchet wheel, and a pawl device adapted to effect a rotation of said ratchet wheel. 90
17. A lubricating device for association with a railway track, involving a lubricant reservoir positioned between the track rails and adjacent the inner side of one of said rails, a plurality of movable wipers spaced along the track for supplying lubricant from the reservoir to the part to be lubricated, said wipers being adapted to extend between the head of the adjacent rail and the flange of a car wheel and to be actuated by the passage of a car over the track, and a guard rail positioned between the track rails and constituting means for limiting lateral movement of car trucks with respect to wipers. 100
18. A lubricating device for association with a railway track, involving a lubricant reservoir, means movable with respect to said reservoir for supplying lubricant to the part to be lubricated, and mechanism for operating said means, said mechanism comprising a plurality of relatively movable members one of which is secured to and movable with a rail of the track so as to be actuated by said rail upon vertical movement of the latter in either direction induced by passage of a railway vehicle over the track. 115
19. A lubricating device for association with a railway track, involving a lubricant reservoir positioned between the track rails and adjacent one of said rails, a device movable with respect to said reservoir for supplying lubricant to the part to be lubricated, said device being adapted to extend between 120
- 55 60 65 70 75 80 85 90 95 100 105 110 115 120 125 130

the head of the adjacent rail and the flange of a car wheel, and means for operating said device, said means being actuated by said rail upon flexure of the latter vertically in either direction induced by passage of a railway vehicle over the track.

20. A lubricating device for association with a railway track, involving a lubricant reservoir, means movable with respect to 10 said reservoir for applying lubricant to the part to be lubricated, and mechanism for operating said means, said mechanism including a pawl and ratchet device and a clutch, said pawl and ratchet device being actuated 15 by said rail upon movement of the latter resulting from passage of a railway vehicle over the track, and said clutch being adapted to release when overloaded.

21. A lubricating device for association 20 with a railway track, involving a lubricant reservoir, means rotatable with respect to said reservoir for applying lubricant to the part to be lubricated, and mechanism for operating said means, said mechanism being actuated by said rail upon vertical movement of the latter in either direction to thereby cause a unidirectional rotation of 25 said rotatable means.

22. A lubricating device for association 30 with a railway track, involving a lubricant

reservoir, a frame within said reservoir, said frame comprising spaced side bars which are independently adjustable vertically, and means rotatably mounted on said bars for transferring lubricant from the reservoir to 35 the part to be lubricated, said means being adapted to extend between an adjacent rail and the flange of a car wheel.

23. A lubricating device for association with a railway track, involving a lubricant 40 reservoir, a frame disposed within said reservoir and vertically and longitudinally adjustable with respect to the latter, a plurality of rotatable disks adapted to dip into the lubricant and to transfer the latter to the 45 part to be lubricated, said disks being adapted to extend between the head of the adjacent rail and the flange of a cooperating car wheel passing thereover, means for adjusting said frame vertically to compensate for 50 their wear and that of the adjacent track rail, chain and sprocket mechanism mounted on said frame for actuating said disks, means mounted independently of said frame for driving said chain and sprocket mechanism, and means for longitudinally adjusting the position of the frame with respect to 55 said driving means.

In testimony whereof I affix my signature.

JOHN R. DERRICK.
